UNITED STATES PATENT OFFICE.

HENRY C. HARRISON, OF PORT WASHINGTON, NEW YORK, ASSIGNOR TO WESTERN ELECTRIC COMPANY, INCORPORATED, OF NEW YORK, N. Y., A CORPORATION OF NEW YORK.

WAVE-ENERGY-TRANSLATING DIAPHRAGM AND METHOD OF MOUNTING SAME.

Application filed July 30, 1924. Serial No. 729,002.

This invention relates to wave energy translating diaphragms and method of mounting the same. More specifically it refers to a diaphragm mounting of a type particularly well adapted for use in telephone transmitters, receivers, phonographs and the like.

The object of this invention is the provision of a diaphragm mounting which will be simple, efficient, cheap to manufacture and wherein the diaphragm is tensioned in a simple and positive manner.

A feature of the invention resides in the provision of means whereby the diaphragm is tensioned and free to vibrate uniformly to each side of its normal resting plane.

Another feature is the provision of means whereby the diaphragm is tensioned progressively to its adjusted period of vibration.

Another feature is the provision of means whereby the diaphragm is yieldingly held during the initial tightening applied to its mounting for removing any unevenness in the blank.

Another feature is the provision of a ring of yieldable material for forcing portions of the diaphragm into circular grooves in the mounting for tensioning the diaphragm uniformly to any desired frequency.

Other features and advantages will appear from the following description and by the claims appended thereto, reference being had to the accompanying drawings in which Fig. 1 is an assembly view of the mounting with the upper ring, the soft metallic ring and the diaphragm partially cut away.

Fig. 2 is a sectional view of the mounting taken approximately on line 2-2 of Fig. 1.

Fig. 3 is a sectional view of the mounting showing the diaphragm positioned between the grooved ring and the soft metallic ring; and

Fig. 4 is a view similar to that of Fig. 3, showing the rings in position when the diaphragm is stretched to its required tension.

Similar reference characters refer to similar parts throughout this description.

The diaphragm mounting of this invention consists of a metallic ring 11 which has a concave-shaped surface 12 and a guide portion 13 adapted for holding a soft metallic ring 14 in adjusted position in the concave portion 12.

The diaphragm 15 is mounted between the

ring 14 of relatively soft metal, such as lead, and the ring 16 which is provided with a plurality of concentric corrugations or grooves 17 made of decreasing depth toward the center as shown in Fig. 2.

The ring 14 and the diaphragm 15 are clamped between rings 11 and 16 by means of a plurality of screws 18 disposed in a circular row around the flange of ring 11 in engagement with similarly disposed threaded holes in the ring 16. The edge of the concave portion 12 is adapted to engage and force the periphery of the diaphragm and ring 14 into the outermost disposed groove 17 of ring 16 through a relatively slight tightening of screws 18. This initial pressure results in stretching the diaphragm uniformly and removes any unevenness in the blank partly due to the fact that the material used for ring 14 is sufficiently malleable to permit a small amount of slippage between the effective surface of the ring 14 in contact with the diaphragm and the corrugated portion 17 in contact with the opposite side of the diaphragm. By applying further pressure on the clamping rings 18 through the tightening of screws 18, concentric portions of the diaphragm are progressively forced into the corrugations 17. The diaphragm is then positively held therein by means of the soft metallic ring 14 which gradually takes the form defined by the cooperating gripping portion of rings 11 and 16 as shown in Fig. 4. The diaphragm 15 may be tensioned to any desired frequencies by changing the pitch of corrugations 17 in the ring 16.

What is claimed is:

1. In combination, a diaphragm, a ring of soft metal, clamping means between which said diaphragm and ring are clamped, said clamping means having corrugations therein, into which portions of the diaphragm are progressively forced by said soft metal ring to tension the diaphragm.

2. In a mounting for a wave energy translating diaphragm, the combination with superposed clamping rings, a ring of malleable material associated with said rings, a diaphragm interposed between one of said clamping rings and the malleable ring, and means formed in one of said rings for stretching said diaphragm uniformly.

3. In a mounting for a wave energy trans-

- lating diaphragm, the combination with a concave-shaped ring, a superposed flat ring, a plurality of concentrically disposed annular members formed in said flat ring, a diaphragm interposed between the concave and the flat ring, and means for forcing portions of the diaphragm into the grooves formed by said members for tensioning said diaphragm uniformly.
- 10 4. In a mounting for a wave energy translating diaphragm, a pair of superposed rings having gripping portions, a diaphragm and a ring of soft material disposed between said portions, tightening means associated with said rings for forcing portions of the soft material into said gripping portions for stretching the diaphragm uniformly.
- 15 5. In a mounting for a wave energy translating diaphragm, the combination with superposed clamping rings, a recessed portion in one of said rings, a plurality of concentric corrugations formed in the other ring, a diaphragm fastening means for securing said diaphragm between said rings, and means interposed between said diaphragm and the recessed portion of the ring for forcing portions of the diaphragm into the grooves of said other ring for tensioning said diaphragm uniformly.
- 20 6. In a mounting, a pair of superposed

rings having cooperating gripping portions shaped to form different geometrical figures, a wave energy translating diaphragm interposed between said rings, and means for causing portions of said diaphragm to take the shape of one of said figures for tensioning said diaphragm uniformly.

35 7. In a mounting, a pair of superposed rings having cooperating portions shaped to form different geometrical figures, a wave energy translating diaphragm and a ring of malleable material interposed between said portions, and fastening means to cause the diaphragm to take the shape of one of 40 said figures and the ring to take the shape of both of said figures for tensioning the diaphragm uniformly.

45 8. The method of mounting and tensioning wave energy translating diaphragms by subjecting the diaphragm and a ring of soft material to an initial pressure between the corrugated and concave surfaces of two clamping rings, and progressively tightening the mounting block for positively holding the diaphragm to its adjusted position.

50 In witness whereof, I hereunto subscribe my name this 25th day of July, A. D., 1924.

HENRY C. HARRISON.
